UNITED STATES PATENT OFFICE.

JOHN STANLEY STULL, OF CHICAGO, ILLINOIS, ASSIGNOR TO WESTERN ELECTRIC COMPANY, INCORPORATED, OF NEW YORK, N. Y., A CORPORATION OF NEW YORK.

ROTATION-COUNTER.

1,262,996.

Specification of Letters Patent. Patented Apr. 16, 1918.

Application filed August 16, 1916. Serial No. 115,204.

To all whom it may concern:

Be it known that I, JOHN STANLEY STULL, a citizen of the United States, residing at Chicago, in the county of Cook and State of Illinois, have invented certain new and useful Improvements in Rotation-Counters, of which the following is a full, clear, concise and exact description.

This invention relates to rotation counters, and more particularly to counters of this type adapted for use in connection with automatic winding machines for counting the number of turns of wire being wound on a spool.

15 One object of the invention is to provide a device capable of withstanding the wear and tear incident to a very high speed of rotation of the driving member. Another object is to provide a device which shall 20 give accurate readings under said conditions of high speed rotation. A further object is to provide a device, the readings of which shall be clear to the operator despite the continuous movement of the parts. An additional object is to provide a device of this 25 character of generally simplified construction and one lending itself to economical manufacture.

In general, the construction comprises a 30 base on which two concentric dials are rotatably mounted. One dial is marked with digits representing the units and tens orders and the other dial is marked with digits representing the hundreds and thousands 35 orders. The dials are positively driven by a differential connection from a suitable shaft. A cover plate is arranged over the dials and is provided with a sight opening through which the digits on the dials are 40 visible. Suitable cam mechanism is provided to move the cover plate back and forth. The arrangement is such that both dials travel continuously in the same direction at different rates of speed. The cover 45 plate and hence the sight openings move with the digits of the hundreds thousands orders during one complete rotation of the units and tens dial after which said cover plate is returned abruptly to initial position.

50 A device embodying the various features of the invention is shown in the accompanying drawings in which:

Figure 1 is a plan view;

Fig. 2 is an enlarged sectional view on plane 2—2, Fig. 1; 55

Fig. 3 is a sectional view on plane 3—3 Fig. 2;

Fig. 4 is a sectional view on plane 4—4 Fig. 2;

Fig. 5 is an enlarged sectional view on 60 plane 5—5, Fig. 3;

Fig. 6 is a sectional view on plane 6—6, Fig. 5;

Fig. 7 is a plan view of a latch member;

Fig. 8 is an enlarged vertical sectional 65 view on plane 5—5, Fig. 3, of one of the terminal gears forming part of the device;

Fig. 9 is a side view of the parts shown in Fig. 8;

Fig. 10 is an enlarged sectional view on 70 plane 5—5, Fig. 3, showing another driven member;

Fig. 11 is a side view of the structure shown in Fig. 10;

Fig. 12 is a view similar to Fig. 10, the 75 section being taken at another diametral plane, and

Fig. 13 is a sectional view on plane 13—13, Fig. 12.

The supporting structure for the device 80 is in the form of a base 1 preferably of metal, which has a pivot stud 2 secured at its lower end therein and extending upwardly therefrom at right angles with the top, the bottom of the base being preferably inclined so that when the base is resting on its bottom the top will be inclined. The block has a chamber 3 concentric with the pivot stud for accommodating the worm wheel 4, a raised seat 5 forming a bearing 85 for the gear hub. Extending transversely through the base and journaled therein is a drive shaft 6 carrying a worm 7 which meshes with the worm wheel, one end of the worm shaft extending from the base so as 90 to be coupled with a suitable driving element, such for example, as an automatic winding machine. Surrounding the chamber 3 is an annular seat having horizontal and vertical walls, 8, 9, which hold the annular internal gear 10 concentric with reference to the pivot stud 2. The internal gear is prevented from rotating by means of one or more screws 11. An apertured disk 12 is mounted concentrically on the 95 worm wheel 4 by means of screws 13. Its

100

worm wheel 4 by means of screws 13. Its

outer edge is beveled and provided with notches 14, there being one hundred such notches in the structure shown.

Secured to and extending upwardly from 5 the worm wheel near its outer edge is a pivot stud 15 carrying a gear pinion 16, a pocket 17 being provided in the worm gear for the pinion and the disk 12 having an opening 18 through which the pinion extends.

Above the disk 12 and concentric therewith is the annular internal gear 18'. This gear is secured by screws 19 to the under side of a circular disk 20, which surrounds 15 a reduced section of the knob structure 21, the latter surrounding the upper end of the pivot stud 2. A nut 22 engaging with the threaded lower end of the knob structure clamps the disk 20 against a shoulder 23 on 20 the knob structure. The knob structure is cored out to form a chamber for the compression spring 24 which abuts against the under side of the head 25 on the pivot stud and the abutment collar 26. The bottom 25 of the spring chamber has an annular groove 27 forming a runway for bearing balls 28 supporting the collar 26. The pivot stud being secured to the base 1, the spring will tend to force the knob structure and 30 the disk 20 secured thereto downwardly to hold the internal gear 18' against the disk 12.

The cylindrical outer surface of the gear 18' forms a continuation of the outer surface 35 of the disk 20 and at its lower end said gear has an annular flange 29. Surrounding the disk 20 and gear 18' is the annular dial member 30, the lower part of this member being enlarged to receive the 40 flange 29 on the gear 18'. At its lower inner corner the member 30 is beveled away to correspond with the beveled outer edge of the disk 12 carried by the worm wheel. At one point the dial member 30 has a vertical 45 pocket 31 for the pin 32 whose tongue 33 normally projects into one of the notches in the disk 12 in order that the member 30 will rotate with the disk 12 and the worm wheel. With the parts in the position 50 shown in Fig. 2, a small rectangular annular clearance space 34 is formed whose function will appear later.

As the worm wheel turns, the pinion 16, by engaging with the fixed gear 10, is rotated and communicates rotation to the gear 18'. However, a differential relationship exists, the gear 10 having a greater number of teeth than the gear 18'. In the construction shown the gear 10 has one hundred and one teeth and the gear 18' has one hundred teeth so that for every revolution of the worm wheel and of the dial member 30 which travels therewith, the gear 18' and the disk 20 to which it is secured, will rotate only a distance of one

tooth or one one-hundredth of a revolution. As clearly shown in Fig. 3, the digits indicating the units and tens orders appear on the upper side of dial member 30 and the digits of the hundreds and thousands orders appear on the disk 20. The two sets of digits are adjacent to each other and each set ranges from 00 to 99. In other words, the range is from 0 to 10,000.

In Fig. 3 the arrangement of the indicating numerals on the dials is clearly shown, and Figs. 1 and 2 show the arrangement and control of the cover plate or sight disk 35 which has the radial sight opening 36. Said plate rests on top of the dial members 20 and 30 but may be slid back and forth in a direction at right angles with the sight opening and for a distance equal to the distance between adjacent indicating numbers on the dials. The cover plate has an opening 37 for receiving the reduced section 38 of the knob or handle 21, the hole being of larger diameter than this section to permit shifting of the disk. The shoulder 39 on the knob holds said cover plate 40 against vertical displacement. To further guide said plate, pins 40 and 41 extend upwardly from the base 1 through slots 42 and 43 therein. The shifting of the plate is accomplished by the engagement of a pin 44 with the cam edge 45 on the dial member 30, the pin extending downwardly from the plate. The cam surface extends spirally and its throw is equal to the distance between successive numbers on the dials. As the outer dial revolves, the cover plate will be shifted accordingly, to cause the sight opening to follow an indication on the inner dial 20 until the end of one revolution of the outer dial, the pin 44, at the end of said revolution, being shifted back to the beginning of the cam 45 and the sight disk being shifted back to normal position to restore the sight opening to the normal sight line. The spring 46 secured to the back of the base 1 presses at its upper end against the extension 47 on the sight disk and tends to shift the disk to hold the pin in firm engagement with the cam surface. The sight disk is therefore the transfer member for carrying over from the units-tens indications to the hundreds-thousands indications. Normally the sight disk is down and the indications 00, 00 are in register with the sight opening. When the tens units dial revolves the indications 01, 02, etc., come successively into register with the sight opening and the cam mechanism shifts the sight disk to cause the sight opening to follow the 00 indication on the hundreds-thousands dial which travels only ¹⁰⁰ as fast as the tens-units dial. When the crest 48 of the cam is under the pin 44 the sight disk will have been shifted its entire distance with the sight opening still in ¹¹⁰ 130

- register with the hundreds-thousands, indications 00. The units-tens dial will be practically at the end of its revolution with its indication 99 in register with the sight slot.
- 5 Then when the pin is released from the end of the cam surface, the sight disk is shifted by the spring 46 to bring the sight opening back to the normal sight line and the indication will be 01. During the next revolution of the tens-units-dial, the sight opening will follow the indication 01, and the tens-units dial will bring the indication 01 to 99 successively into the sight opening, and at the end of a revolution the sight opening will be dropped back to the normal sight line to indicate 02. Thus the hundreds-thousands order indications will always be visible while the units-tens indications are being carried past the sight opening and the operator can readily observe at any time how many revolutions have been made by the drive shaft 6 which is connected with the winding or other machine.
- 25 Re-setting of the dials to zero position is accomplished by raising the knob 21 and turning it until the normal positions are reached. As the dial 20 and its driving gear 18' are secured to the knob structure 30 by the nut 22, raising of the latter will lift them. On account of the clearance space 34 the dial member 30 will not follow immediately but after the clearance space has been taken up, said dial will be carried upwardly by the flange 29 and the pin 31 will be released from the notched disk 12. The knob 21 can be raised until the ledge 49 abuts against the head 25 of the pivot stud 2, the permissible vertical movement of the knob being sufficient to bring the gear 18' above and out of engagement with the gear pinion 16. Therefore, when the knob is raised, the hundreds-thousands dial member will be disengaged from its driving pinion 16 and the units-tens dial member will be disengaged from its driving disk 12. The knob is now turned and the dial members are brought back to normal position.
- To limit the re-setting movement, latching members are provided as shown in Figs. 5, 8 and 9, a latch pin 50 being arranged radially in the gear 18' and projecting upwardly a certain distance from ledge 29 into clearance space 34. In the dial member 30, there is a radial notch 51 which is vertically above the latch pin 50 when the zero indications on the dial members are in radial alinement. When the dial structure 20 is first raised by the knob structure after a counting operation, the top of the latch pin 50 will engage with the overhanging wall of the dial member 30 at a point away from the notch 51, and when the dial members are relatively rotated, the pin eventually drops into the notch, the clearance space 34 is en-

tirely eliminated, and the dial members are locked together with their zero indications in alinement, and the locked dial members are then rotated until the zero indications are in the normal sight line in register with the sight opening. To facilitate accurate re-setting to the sight opening, the latch mechanism best shown in Figs. 5, 6, 7, 10 and 11 is provided. A bore 52 extending radially through the base 1 from one side thereof contains a latch bar 53, this bar being guided at its inner end in the passage-way 54 and at its outer end by the plug 55 which screw threads into the bore outer end. The inner end 56 of the bar normally projects into the space 57 between the base 1 and the cylindrical side of the dial member 30. The lower edge of the end 56 is beveled as clearly shown to coöperate with the outer beveled corner of the annular ledge 58 extending from the dial member 30 below the end 56. A compression spring 59 between the plug 55 and the collar 60 on the bar 53 tends to hold the bar inwardly with the end 56 in the space 57. The ledge 58 has the notch 61 adapted to be brought into position below the bar end 56 when the dial member 30 is rotated. Normally, that is, when the zero indications of the dials are in register with the sight opening, this notch 61 is below the end 56 of the latch bar, and as soon as the disks rotate the notch will move away from the bar so that when the knob is raised for re-setting operation the beveled corner of ledge 58 will encounter the beveled bar end 56 and the bar will be shifted away, and when the dial members have been raised the full vertical distance by the knob the ledge 58 will be in front of the bar end. Then when the dial member 30 is rotated the notch 61 is brought into register with the bar end and the bar is released and shifted by its spring into the notch and further turning of the dial disk is prevented, the disk being then in position with its zero indications under the sight opening. When the knob is raised and turned to rotate the dials, the dial 30 may be caught by the latch bar 53 before it is locked to the dial member 20 by the pin 50 and notch 51, or the dial 30 may first be locked to the other dial structure and then to the base. In either case turning of the knob until stopped by the latches will result in re-setting of the dial members with their zero indications in the normal line of sight under the sight opening, and when the knob is then released, the spring 24 will push the dial structures down in their normal position with the gear 18 in mesh with the pinion 16 and the dial 30 reengaged by pin 32 with the notched disk 13, this disk remaining stationary during the re-setting operation. During a re-setting operation, the sight disk is also raised but is prevented

from rotating by the pins 40 and 41, and during re-setting the beginning of the cam surface will be brought back to the pin 44 to bring the sight opening back to the normal sight line.

5 What is claimed is:

1. A rotation counter, comprising a plurality of dials, a movable member having a sight opening therein through which said 10 dials are visible, and means acting concurrently with one of said dials for moving said member to cause said sight opening to travel with another of said dials.

2. In a device of the class described, the 15 combination with two dial members one bearing numbers of one decimal order and the other bearing numbers of a higher decimal order, means for moving the dial member with lower decimal order indications 20 thereon faster than the other dial member, a plate having a sight opening, means controlled by the dial member with the lower decimal order indications thereon for moving said plate at a rate to remain in registration for periods of time with successive 25 indications on the other dial member and to be shifted back into registration with a succeeding indication in order to carry over from the lower order dial member to the 30 higher order dial member.

3. The combination with two dial members having decimal order indications thereon, of means for causing one of said members to travel faster than the other, carrying 35 mechanism comprising a plate with a sight opening and means controlled by one of said members to shift the plate to cause the sight opening to travel a predetermined distance with successive indications on the 40 other member.

4. The combination with two dial members, of means for causing one of said members to travel faster than the other, a sight plate having a sight opening, and cam mechanism controlled by one of said members to shift said plate a predetermined distance 45 with each successive indication on the other member to carry over the decimal indications from one member to the other.

50 5. In combination, two concentric dial disks one of which has dial indications thereon of higher decimal order than the other, means for rotating the lesser order dial disk faster than the higher order dial 55 disk, a plate having a sight opening through which the dial indications may be observed, and means for moving said plate to hold the sight opening in registration for a certain period for each successive indication 60 on the higher order dial disk and for restoring it after each such movement to bring the sight opening into registration with the following indication.

6. In combination, two concentric dials 65 one having indications of one decimal order

thereon and the other having decimal indications of a higher order thereon, means for causing the lower order dial to travel faster than the higher order dial, a plate over said dials having a sight opening through which 70 the dial indications may be observed, a spring tending to hold the plate with the sight opening in a normal sight line, and cam mechanism controlled by the lower order dial for shifting said plate to cause 75 the sight opening to remain in registration for a predetermined distance with each indication on the higher order dial and to release the plate after such shift to permit the spring to restore it to carry the sight opening back to the normal sight line in registration with the succeeding higher order indications whereby to carry over from the 80 lower order indications to the higher order indications.

85 7. In combination, two concentric dials one having indications thereon of a low decimal order and the other having indications thereon of a higher decimal order, means for causing said higher order dial to 90 rotate only one one-hundredth of a revolution for each complete revolution of the low order dial, a sight plate over said dials having a sight opening for registering with said indications, and means for successively 95 moving said plate the distance between two higher order indications and for restoring the plate after each such movement whereby the sight opening will remain in registration with each indication on the higher order 100 disk during such movement and shifted back after such movement to be in registration with the following indication whereby carry-over is effected from the low orders to the 105 higher orders.

8. In counting mechanism of the class described, the combination of two concentric dial disks having decimal indications adjacent their contiguous edges, indications on the outer dial disk being of a lower decimal order and those on the inner disk of a higher decimal order, differential gearing mechanism for rotating the outer dial disk faster than the inner dial disk at a rate proportional to the difference in decimal orders of the respective disks, a sight plate over said disks having a sight opening through which the disk indications may be observed, a spring tending to hold said plate in normal position with the sight opening in a normal sight line, said outer dial disk having a cam surface, and a pin extending from said plate into engagement with said cam surface, said cam mechanism and spring co-operating to shift the plate to cause the sight opening to remain in registration for a fixed period with each higher order indication and to be shifted back after each period to restore the sight opening to the 110 normal sight line in registration with the 115 120 125 130

succeeding higher order indication whereby carry-over is effected from the lower order to the higher order.

9. In counter mechanism, the combination of a supporting base, a pivot stud extending upwardly therefrom, a driving member supported in said base and journaled on said pivot stud, an inner dial member adapted to rotate about said pivot stud, an outer dial member also arranged to rotate about said pivot stud, said inner dial member having indications thereon of a higher decimal order and said outer dial member having indications of a lower decimal order, differential gearing mechanism connecting said dial members with said driving member to cause said outer dial member to travel faster than the inner dial member in a ratio proportional to the ratio between the low and high order indications, and a plate over said dial members having a sight opening through which the indications may be read as the dial members rotate.

10. In counter mechanism, the combination of a supporting base, a pivot stud extending upwardly therefrom, a driving member supported in said base and journaled on said pivot stud, an inner dial member adapted to rotate about said pivot stud, an outer dial member also arranged to rotate about said pivot stud, said inner dial member having indications thereon of a higher decimal order and said outer dial member having indications of a lower decimal order, differential gearing mechanism connecting said dial members with said driving member to cause said outer dial member to travel faster than the inner dial member in a ratio proportional to the ratio between the low and high order indications, a plate shiftable on said dial members and having a sight opening for registering with indications on the dial members, means controlled by the outer dial member for shifting said plate to cause the sight opening to follow and to remain in full registration with each higher order indication, and means for restoring the plate after each such shift and to bring the sight opening into registration with the succeeding higher order indication, said shifting sight opening serving to carry-over from the lower to the higher indications.

11. A rotation counter of the type described, comprising a supporting base, a pivot stud carried thereby, a driving member rotatably mounted on said stud, a plurality of concentric dials, the faces of which normally lie in the same plane, the outer dial being detachably connected to said driving member, differential gearing connecting the inner dial with said driving member whereby said inner dial may be rotated slower than said outer dial, means for moving said inner dial out of engagement with said gearing, means whereby such

disengaging movement of said inner dial causes said outer dial to be moved out of engagement with said driving member, and means whereby said inner and outer dials may be rotated back to normal position after they have been disengaged from said differential gearing and said driving member respectively.

12. A rotation counter of the type described, comprising a supporting base, a pivot stud carried thereby, a driving member rotatably mounted on said stud, a plurality of concentric dials, the outer one of which is detachably connected to said driving member and adapted to rotate therewith, differential gearing connecting the inner dial with said driving member whereby said inner dial is rotated slower than said outer dial, means for lifting said inner dial out of engagement with said differential gearing and for resetting said dial, and abutments on said inner and outer dials for causing said outer dial to be raised with the inner dial and to be disconnected from said driving member whereby both of said dials may be set simultaneously.

13. A rotation counter comprising a supporting base, a pivot stud mounted thereon, a driving member journaled on said stud and having peripheral notches, an outer dial, a projection thereon adapted to engage with said notches whereby said dial is normally rotated with said driving member, an inner dial, gearing normally connecting said inner dial with said driving member whereby said inner dial is rotated slower than the outer dial, means for moving said inner dial out of engagement with said gearing, means whereby the disengagement of said inner dial causes said outer dial to be moved to withdraw said projection from said notches to thereby disconnect said outer dial from said driving member, and means whereby said dials may be rotated back to normal position after they have been disengaged from said driving member.

14. A rotation counter comprising a supporting base, a pivot stud mounted thereon, a driving member journaled on said stud and having peripheral notches, an outer dial, a projection thereon adapted to engage with said notches whereby said dial is normally rotated with said driving member, an inner dial, gearing normally connecting said inner dial with said driving member whereby said inner dial is rotated slower than the outer dial, means for moving said inner dial out of engagement with said gearing, means whereby the disengagement of said inner dial causes said outer dial to be moved to withdraw said projection from said notches to thereby disconnect said outer dial from said driving member, means whereby said dials may be rotated back to normal position after they have been disen-

- gaged from said driving member, and means for preventing a reconnection of said dials with said driving member after said dials have been disengaged therefrom and before 5 the same have been restored to normal, but permitting such reconnection after said dials have been rotated back to normal.
15. A rotation counter of the type described, comprising a supporting base, a 10 pivot stud carried thereby, a driving member rotatably mounted on said stud, a plurality of concentric dials, the faces of which normally lie in the same plane, the outer dial being detachably connected to said 15 driving member, differential gearing connecting the inner dial with said driving member whereby said inner dial may be rotated slower than said outer dial, means for moving said inner dial out of engage-
- ment with said gearing, means whereby 20 such disengaging movement of said inner dial causes said outer dial to be moved out of engagement with said driving member, means whereby said inner and outer dials may be rotated back to normal position after 25 they have been disengaged from said differential gearing and said driving member respectively, and means for preventing a reconnection of said dials with said gearing and said driving member after the 30 same has been disengaged therefrom and before said dials have been restored to normal, but permitting such reconnection after said dials have been restored to normal.

In witness whereof, I hereunto subscribe 35 my name this 8th day of August, A. D. 1916.

JOHN STANLEY STULL.
